MASS SPECTROMETER

Charles F. Robinson, Pasadena, Calif., assignor, by mesne assignments, to Consolidated Electrody namics Corporation, Pasadena, Calif., a corporation of California

Filed June 25, 1956, Ser. No. 593,560

8 Claims. (Cl. 250—41.9)

This invention relates to mass spectrometry and particularly, although not exclusively, to solids mass spectrometry.

In many types of solids mass spectrometers the ion source develops ions with a wide energy spread, making accurate resolution in conventional analyzing systems exceedingly difficult. I have now developed an instrument in which this problem is overcome and by means of which this heretofore objectionable characteristic is used to advantage. Further, and of particular importance, the instrument of the invention permits selective analysis of ions originating in different regions of such a source. In a spark source, for example, I am able to detect small differences in the composition of the two electrodes as a result of the ability to selectively analyze ions originating first from one and then the other of the electrodes.

Whereas certain ion sources inherently produce ions of widely different energy in different regions of the source, other ion sources are characterized by the absence of any substantial energy spread in the ionized particles. This invention depends upon and hence contemplates inducing a significant energy spread if applied to an ion source which does not inherently develop this required energy spread.

In its general application the invention comprises a mass spectrometer having an ion source, a mass resolving system, and ion collecting means, the combination comprising means for imparting different energies to ions formed in different regions of the ion source and means for adjusting the mass resolving system to pass only ions occurring within a given energy band, such band including less than the totality of energies produced within the source. In a preferred form the instrument may include a spark source, an energy filter, means for causing ions to enter the filter from the source, means operable to enable the filter to pass only ions of an energy band less than the energy spread of the ions developed in the source, means for varying the operation of the source to cause ions originating within different regions thereof to fall in the pre-selected energy band, a mass analyzer into which ions passing the filter are injected, and collecting means for collecting ions focused thereon by the analyzer.

In the above described instrument, for example, the high voltage D.C. supply for accelerating ions into the resolving system can be connected alternately to the two electrodes of the source whereupon the ions formed first from one electrode and then the other will possess a definite fixed kinetic energy upon emergence from the ion source, ions from the other electrode emerging from the ion source with energies distributed through a very wide range. By introducing these ions to an electrostatic energy filter in which the voltages are suitably adjusted, it is possible to arrange that the electrostatic filter will pass most of the ions formed on the electrode whose potential is fixed, and reject most of the ions formed

2

on the electrode whose potential is varying through a wide range.

The invention will be understood in conjunction with the accompanying drawing, in which:

Fig. 1 is a schematic diagram of a simplified embodiment of the invention;

Fig. 2 is a schematic diagram of apparatus in accordance with the invention involving a spark source;

Fig. 3 is an enlarged perspective view of the electrode array disposed between the electrostatic filter and the analyzer in the apparatus of Fig. 2; and

Fig. 4 is a graphic diagram of the operation of the apparatus of Fig. 2.

The apparatus of Fig. 1 includes an ion source 10, an electrostatic filter 11, a magnetic mass analyzer 12, a collector system 13 and a sensing and recording circuit 14. The ion source 10 is intended to represent any ion source characterized by production of ions of widely varying energy. The particular source shown includes an ion gun 16 oriented to direct an ionizing beam against the surface of a sample 17 contained in the face of a repeller electrode 18. The ion gun may be any of a variety of conventional ion sources such, for example, as the ion gun described by Moak, Reese and Good in "Nucleonics," volume 9, page 18 (1951). Ions formed at the sample 17 are collimated and accelerated by electrodes 19, 20. A voltage supply circuit 22 for the accelerating electrodes is shown schematically. Plates 24, 25 of the electrostatic filter 11 are connected to opposite sides of a D.C. supply 26 so that a positive potential is imposed on the plate 25 and the negative potential on the plate 24. Of the ions entering the filter 11, only those of a given energy spread determined by the potential applied between plates 24 and 25 and by the width of the aperture in electrode 28 will traverse the aperture in a first resolving electrode 28 for entry into the magnetic analyzer 12.

The analyzer 12 is represented by a magnet structure defining the outlines of a conventional ion resolving transverse magnetic field and showing the course of ion travel therein. In the analyzer ions of a certain mass depending on ion velocity and magnetic field strength are focused through the aperture in a second resolving electrode 29 onto the first dynode of an electron multiplier 30 which, in this particular instance, forms the collection system 13.

It is the purpose of this invention to permit the retention for analysis of ions of a given mean energy, as for example those formed at the surface of the sample 17, at the same time rejecting ions of a different mean energy, such as those formed from background gases in the space between the sample 17 and first slit 19.

Operation of the instrument is as follows: A sample to be analyzed is placed in the receiving cup of the repeller electrode as illustrated. An ionizing ion beam is directed against the surface of the sample with sufficient energy to achieve nonfractionating ionization. These ions together with others formed in the source are expelled therefrom at a velocity dependent upon the potential established across the source. In the filter 11 only ions of a given mean energy, in this example the mean energy exhibited by ions formed by bombardment at the sample surface, are transmitted. All ions of energy differing substantially from those originating at the sample surface will be deflected by the electrostatic energy filter plates 24 and 25, so as to fail to pass through the aperture in electrode 28, but will strike the surface thereof and be discharged thereon. The ions passing through the resolving aperture into the analyzer are resolved by the magnetic field, selectively focused on the resolving aperture of the analyzer, and sensed in conventional fashion. In the instrument of

Fig. 1, selectivity achieved by the invention is desirable to permit an accurate analysis of ions formed at a surface having a given potential and to discriminate against ions formed at other potentials, as for example ions formed from background gases. This is made possible in the apparatus of Fig. 1 by imposing a substantial voltage between electrodes 18, 19 and 20, this imposed voltage causing the potential in most of the free space surrounding electrode 18 to be substantially different from the potential of electrode 18 so that ions formed in that space possess substantially different kinetic energies from ions formed at electrode 18. In the apparatus of Fig. 2, ions are inherently formed with large energy spread, and the circuits are arranged so as to take advantage of that fact.

In the instrument of Fig. 1, selectivity achieved by the invention is desirable to permit an accurate analysis of ions developed at a surface having a given potential and to exclude ions formed at other potentials, as for example ions formed from background gases. In the apparatus of Fig. 2, a large energy spread in the ion source is purposely induced so that comparative analysis may be made with the mass resolving system of the invention.

The instrument shown in Fig. 2 comprises an ion source 40, an electrostatic filter 41, an analyzer 42, collecting system 43, and sensing circuit 44. The ion source consists of a pair of electrodes 46, 47 to which a high voltage D.C. supply 48 may be alternately connected through switch 49 and potentiometers 50, 51. An R.F. oscillator 52 is connected across the electrodes through a transformer 53. A grounded electrode 54 accelerates ions formed in the spark developed between electrodes 46, 47 into the electrostatic filter 41.

A D.C. supply 56 is connected to develop a positive potential at plate 57 and a negative potential at plate 58 of the filter. A so-called wiper electrode array consisting of a grounded first resolving electrode 68 and a sampling electrode 69 is preferably interposed between the filter 41 and the analyzer 42 for purposes which will be described.

The settings of the energy filter are well known in the mass spectrometer art. As an illustrative example we may say that where plates 57 and 58 are spaced 1 centimeter apart and held at a difference of potential of 500 volts, having a mean radius of curvature of 30 centimeters, ions having a kinetic energy of 7,500 electron volts are passed at optimum efficiency and if aperture 68A is 2×10^{-2} cm. wide and is placed immediately adjacent plates 57 and 58, ions having an energy spread of 15 volts (that is to say, ions having a kinetic energy of $7,500 \pm 7.5$ volts) are passed by the electrostatic filter.

The analyzer 42 is illustrated schematically as a magnet pole 72 defining the outline of a transverse magnetic field, and a second resolving electrode 73 through which ions of a particular mass are focused on the first dynode of the electron multiplier which forms the collection system 43. The electron multiplier is connected to a switch 76 which in turn is connected to two integrating circuits 77, 78, the outputs of which are connected to the sensing system 44. The wiper electrode 69 is connected to an integrating network 80 which in turn is connected to operate switches 49 and 76 on the ion source high voltage supply and on the output integrators respectively.

The electrodes 68, 69 forming the wiper system intermediate the electrostatic filter and the analyzer are shown in perspective in Fig. 3. The electrode 68 has a vertically oriented aperture 68A. The wiper electrode 69 has a vertically restricted aperture 69A so that the vertical extremities of an ion beam, illustrated at 82, form shadows 82A, 82B on the wiper electrode 69. The width of the aperture 68A defines the energy spread of the ions admitted to the magnetic analyzer, whereas the vertical height of the aperture 69A limits the height of the beam admitted to the analyzer.

The integrating network 77, 78 and 80 may be of the type of the Weston Model 1473, available from the Weston Electric Instrument Corporation, Newark, New Jersey, and described in Weston Engineering Notes, vol. 10, No. 2, page 6, December 1955.

The operation of the apparatus of Fig. 2 may be described with relation to an actual analysis and with the aid of the graph of Fig. 4. Electrode 46 of the ion source may constitute a zone-refined silicon standard and electrode 47 a silicon of unknown purity. The electrostatic deflection system and its associated aperture 68A are set to pass ions whose energies lie in a narrow band centered on the applied high voltage V_0 (this being the output voltage of the high voltage supply 48) that is, at or near the potential of whichever of electrodes 46 and 47 is directly connected to the high voltage supply. By switching the high voltage supply from electrode 46 to electrode 47 by means of switch 49, it is possible for the electrostatic deflection system to sample selectively ions originating respectively from either electrode. This comes about because if the electrostatic deflection system is set so as to pass ions of energy V_0 and the high voltage supply 48 is connected to (for example) electrode 46, ions from electrode 46 are passed freely by the electrostatic energy filter while ions formed at electrode 47, whose potential with respect to ground varies widely with time according to the equation $V_{47} = V_0 + V_{53} \sin \omega t$, where V_{53} is the peak voltage amplitude on the secondary of transformer 53 and ω is the frequency of oscillation of R.F. oscillator 52, are passed only during the instants that V_{47} lies within the narrow band of energies passed by the electrostatic energy filter. In this mode of operation it is understood that V_{53} is large compared to the energy pass band of the electrostatic filter.

The ions passed by aperture 68A are further resolved in the magnetic resolving system 42 and second resolving electrode 73, and the output of collector 43 is fed selectively to one or the other of integrators 77, 78 through switch 76 which is ganged to switch 49. Thus, integrator 77 may be made to give the integrated ion current with respect to a certain atomic species of ions originating at electrode 46 and integrator 78 to give similar intelligence with respect to ions of the same atomic species originating in electrode 47. Thus, the difference in reading between integrators 77 and 78 constitutes a measurement of the abundance of the selected impurity on which the system is focused which, for instance, may be boron. This difference reading is obtained even though the instrument background in the neighborhood of the boron peaks may be much higher than the difference to be detected.

The operation is illustrated graphically in Fig. 4 in which curve B represents the electrical signal applied, for example, to electrode 46 of the source, and curve 55 "a" represents the D.C. signal applied to electrode 47 of the source with switch 49 in the dotted line position. If the electrostatic filter 41 is set to pass a band represented by the dotted lines on either side of D.C. voltage "a," only those ions originating at electrode 46 in the fractional cycles represented by the coincidence of curve B and the band pass of the electrostatic filter will reach the analyzer section 42. Substantially all of the ions produced at electrode 47, however, will be passed to the analyzer section while, as indicated, virtually all 60 of the noise represented by ions produced at electrode 46 will be excluded. The converse is true, as illustrated by the second curve of Fig. 4, and with switch 49 in the solid line position as illustrated.

Potentiometers 50, 51, are not essential to the operation of the apparatus of Fig. 2 but they do enable a selectivity control. By setting the potentiometers at their respective end points, one or the other of the electrodes is connected directly to the source and a maximum selectivity is achieved. At the other extreme, if the two 70 potentiometers are set at mid-point, there is no selec-

tivity. Since the selectivity of the source is a function of the potential difference between the electrodes 46, 47, manipulation of the potentiometers 50, 51 as described permits a control on this selectivity.

In the detection of trace impurities the ion detector is preferably an electron multiplier as shown, and integrators 77, 78 may be simple decade counters counting pulses from the multiplier which in effect constitute the count of individual ions. In this mode of operation, switch 49 can be used to reverse the direction of the count in a single counter, so that a single counter can be used to show directly the difference between the count corresponding to electrode 46 and that corresponding to electrode 47.

It is preferable that the reading intervals on electrodes 46 and 47 be equivalent not in terms of clock time but in terms of total usable ion current produced by the ion source. It is for this purpose that wiper electrode 69 is preferably embodied in the apparatus. The current developed at this electrode through impingement of a portion of the ion beam thereon, as shown in Fig. 3, is integrated in integrator 80, and switches 49 and 76 are controlled as a function of the integrated current developed at the wiper electrode. From a practical standpoint it is desirable for the switching action to take place several times during an analysis so that the tripping level of the wiper electrode current integrator 80 should correspond to about one-tenth or less of the total current necessary for obtaining the desired measurement.

The sensing system 44 may consist of any of the many typical indicating or recording systems suitable for accommodating the output of the integrating system as illustrated.

I claim:

1. A mass spectrometer comprising a spark ion source having at least two electrodes, an A.C. source and a D.C. source connected across the electrodes, an energy filter, means for causing ions to enter the filter from the source, means operable to enable the filter to pass only ions of a given energy band, means for reversing the connection of the electrodes to the D.C. source to alternately cause ions originating at different ones of the electrodes to fall in said energy band, a mass analyzer into which ions passing the filter are injected, and collecting and measuring means for collecting and measuring ions focused thereon by the analyzer.

2. Apparatus according to claim 1 wherein the means for reversing the connection of the electrodes to the D.C. source is operable responsive to the integrated output of the collecting means.

3. Apparatus according to claim 1 wherein the means for reversing the connection of the electrodes to the D.C. source is operable as a function of the ion beam intensity passing from the filter into the analyzer.

4. A mass spectrometer comprising an ion source, a mass resolving system, ion collecting and measuring means, energy selecting means, means operable to energize the energy selecting means for selectively passing to the collecting means ions originating at a given predetermined position in the source and which are within a narrow band of kinetic energies and representing substantially less than the totality of ions formed in the source, and means for varying the potential distribution within the source so that ions formed in different parts of the source lie within the band of energies passed by the energy selecting means.

5. A mass spectrometer comprising an ion source, a

mass resolving system, ion collecting and measuring means, energy selecting means, means operable to energize the energy selecting means for selectively passing to the collecting means ions originating at a given predetermined position in the source and which are within a narrow band of kinetic energies and representing substantially less than the totality of ions formed in the source, and means for comparing the output of the collecting and measuring means at a given mass for different potential distributions within the ion source.

5 6. A mass spectrometer comprising an ion source, a mass resolving system, ion collecting and measuring means, energy selecting means, means operable to energize the energy selecting means for selectively passing to the collecting means ions originating at a given predetermined position in the source and which are within a narrow band of kinetic energies and representing substantially less than the totality of ions formed in the source, and means for automatically and continuously comparing the 10 output of the collecting and measuring means at a given mass for different potential distributions within the ion source.

15 7. A mass spectrometer comprising an ion source, a mass resolving system, ion collecting and measuring means, energy selecting means, means operable to energize the energy selecting means for selectively passing to the collecting means ions originating at a given predetermined position in the source and which are within a narrow band of kinetic energies and representing substantially less than the totality of ions formed in the source means for varying the potential distribution within the source, means for comparing the output of the collecting and measuring means at a given mass for different potential distributions within the ion source, and means automatically recording the difference output through a predetermined period of time.

20 8. A mass spectrometer comprising an ion source, a mass resolving system, ion collecting and measuring means, energy selecting means, means operable to energize the energy selecting means for selectively passing to the collecting means ions originating at a given predetermined position in the source and which are within a narrow band of kinetic energies and representing substantially less than the totality of ions formed in the source means for varying the potential distribution within the source, means for comparing the output of the collecting and measuring means at a given mass for different potential distributions within the ion source and means automatically recording the difference output through a period of time sufficient for the ion source to deliver a predetermined total charge.
